UNITED STATES PATENT OFFICE.

LEROY E. MEYER, OF CUYAHOGA FALLS, OHIO, ASSIGNOR TO THE FIRESTONE TIRE AND RUBBER COMPANY, OF AKRON, OHIO, A CORPORATION OF OHIO.

DESIGN FOR A RUBBER HEEL.

51,815.

Specification for Design.

Patented Feb. 26, 1918.

Application filed October 31, 1917. Serial No. 199,593. Term of patent 14 years.

To all whom it may concern:

Be it known that I, LEROY E. MEYER, a citizen of the United States, residing in Cuyahoga Falls, in the county of Summit, State of Ohio, have invented a new, original, and ornamental Design for Rubber Heels, of which the following is a specification, reference being had to the accompanying drawings, forming a part thereof.

In the drawings Figure 1 is a view of the lower side of a rubber heel showing my new

design, Fig. 2 is a sectional view of the heel on line "2—2" of Fig. 1, and Fig. 3 is a view of the upper side of the heel.

I claim:

The ornamental design for a rubber heel as shown.

LEROY E. MEYER.
